UNITED STATES PATENT OFFICE.

FRANK WATTS BURPEE, OF FAIRHAVEN, WASHINGTON, ASSIGNOR TO LETSON AND BURPEE, OF FAIRHAVEN, WASHINGTON, AND VANCOUVER, CANADA, A FIRM.

SHINGLE-MACHINE.

SPECIFICATION forming part of Letters Patent No. 760,610, dated May 24, 1904.

Application filed February 27, 1903. Serial No. 145,422. (No model.)

To all whom it may concern:

Be it known that I, FRANK WATTS BURPEE, a citizen of the Dominion of Canada, (but having declared my intention of becoming a citizen of the United States of America,) and a resident of the town of Fairhaven, in the county of Whatcom and State of Washington, have invented certain new and useful Improvements in Shingle-Machines, of which the following is a specification.

My invention relates to improvements in machines adapted to saw shingles, and has special reference to an apparatus of this class known as an "upright" shingle-machine.

Among numerous objects attained by this invention and readily understood from the following specifications and accompanying drawings, included as a part thereof, is the production of a simplified and efficient shingle-machine embodying essential constructive features throughout the carriage, feed-works, and various other parts which simplifies the construction of the machine, increases the rapidity of the carriage, insures a smooth and steady travel thereof, and imparts thereto a uniform speed throughout the cutting portion of its forward travel, a relatively quick return, and a comparatively slow motion during that portion of its travel in which the setting of the block occurs.

The above-mentioned and other objects equally as desirable are attained by the constructions, combinations, and arrangement of parts, as disclosed on the accompanying drawings, set forth in this specification, and succinctly pointed out in the appended claims.

With reference to the drawings filed herewith and bearing like reference-characters for corresponding parts throughout, Figure 1 is a view in perspective of the machine, on small scale, looking in the direction indicated by the arrow marked 1 in Fig. 9. Fig. 2 is a view in perspective of the machine, on large scale, viewed as Fig. 1 and indicated with the greater portion of the husk-frame and a part of the track-frame broken away. Fig. 3 is a view in side elevation of the mangle-rack of the feed-works. Fig. 4 is a view in transverse section of said rack, on large scale, taken

on line 4 of Fig. 3 viewed as the arrows indicate and shows the driver engaged with the rack. Fig. 5 is a view in side elevation of the truck-frame employed on the carriage and indicates same with the shelf of the bracket in longitudinal section taken on line 5 of Fig. 6 and shows a portion of the carriage-base in relative position. Fig. 6 is a view of said truck-frame in vertical transverse section, taken on line 6 of Fig. 5 looking as the arrows fly. Fig. 7 is a view of the machine in perspective looking from the point indicated by the arrow marked 7 in Fig. 9 and indicated with portions of the set-works and husk-frame broken away. Fig. 8 is a view of the husk in perspective and indicated with the saws and receiving-table removed. Fig. 9 is a plan view of the machine on small scale. Fig. 10 is a plan view of the cam and supporting-bracket employed to actuate the lever of the set-works, and Fig. 11 indicates said cam and bracket in transverse section on line 11 of Fig. 10 viewed as the arrows fly. Fig. 12 is a perspective view of the mangle-rack-supporting spring.

This shingle-machine includes a suitable vertically-disposed track-frame 14, a carriage 15, operatively mounted in said frame, a suitable husk-frame, as 16, and attendant mechanism, as the feed-works 17, suitable set-works, saw-arbors, and the like.

In the present embodiment, the track-frame 14 comprises an open rectangular frame consisting of vertically-disposed wooden end pieces 18 and top and bottom pieces, as a beam and sill, composed of wood and respectively marked 19 and 19'. In the lower portion of this frame a metal track-bed, as 20, is suitably secured and comprises a horizontally-disposed channel-beam set with the web toward the husk-frame. A section of track, as 21, is placed upon the upper surface of the top wall of this bed adjacent the free edge, and sections of the web of the bed are preferably cut away to reduce the weight of the structure, and a step-block, as 22, or the like is preferably placed on the lower beam or sill 19' midway its length to support the track-bed.

The carriage 15 is formed with a base 23,

composed of a single section of timber of extended length and preferably rectangular in cross-section, and on the under side of this base adjacent the ends suitable trucks, as 24, 5 Figs. 5 and 6, are arranged with the axles 25 disposed transversely said surface and the wheels 26 substantially midway the width of the base in alinement with each other, so that the carriage will thereby be operatively supported on track 21. Upon this base is securely seated an upright iron frame 27, which consists of separated end pieces 28 and a top and bottom plate, (marked, respectively, 29 and 30,) and which are conveniently secured to the 10 ends to respective extremities of said end pieces by bolts or the like passed through the plates and through suitable lugs provided at the desired points on the end pieces. These end pieces are rendered of plate metal, and 15 each comprises a vertically-disposed stem 31, having a horizontal foot-piece 32, projecting laterally from one edge at the lower end, and a bracket 33 at the upper end, projecting from the stem in the same direction as the foot, and 20 at the outer extremity of said foot a downwardly-projecting heel, as 34, is arranged to engage the side of the carriage-base 23, and at the outer end of said bracket an upwardly-extending lug 34 is formed thereon, to which 25 the top plate 29 is secured. These end pieces are connected at the inner ends of the bracket parts by a suitable horizontally-disposed distance-bolt, as 36, and the frame 27 is fastened to the carriage-base by suitable bolts 30 passed through the bottom plate 30, with the 35 heels 34 resting against the front side of said base relatively to the position taken by the sawyer, as designated by the letter A in Fig. 1, and this frame is rigidly secured to the 40 base and firmly supported in position thereon by means of diagonally-disposed truss-rods, as 35, one of which is placed at each side edge of the frame. These rods are oppositely disposed relatively to each other and are each 45 rendered of suitable length to reach from the top edge of bracket 33 of a respective end piece to and through the adjacent end portion of base 23, and each rod is formed with suitable screw-threads on each extremity adapted 50 for the engagement of suitable nuts, as 35', at the upper end, by which the rod is securely locked to a laterally-projecting lug 37, formed on said bracket, and a nut, as 38, on the lower end beneath said base, by the adjustment of 55 which the rod is drawn to the required tension to rigidly brace the frame.

Along the front side of the beam of the track-frame an inverted angle-iron, serving as a track 39, is conveniently secured to said beam, with the downwardly-projecting web 39' lying beyond said side, and this track is rendered of suitable length to extend throughout the length of travel of the carriage and is adapted for the engagement therewith of 60 suitable slides 40, which are secured to the

top plate 29 of the carriage. These slides include upwardly-extending lugs, as 41, secured to the back edge of plate 29, so as to rest between said web 39' and beam 19 adjacent each end of said plate. These lugs are rendered of suitable height to slidably engage the back side surface of web 39', and suitable angle-brackets, as 42, are secured to said top plate of the carriage to slidably engage the front side of said web. 75

The trucks 24, Figs. 5 and 6, each comprises a base-plate 43, which is substantially equal in width to the width of the bottom surface of the carriage-base and of considerable length and is formed with a suitable opening 80 44 for the truck-wheel 26. This opening is greater in width than the depth of the hub of said wheel and is located midway the width of the plate adjacent one end, and at each side of this opening suitable half-boxes 45 are 85 formed on the bottom surface of the plate to afford bearing for the frame on the end portions of an axle 25, fixedly secured in said wheel. At one side edge of this base-plate at the half-box is secured a downwardly-extending bracket 46, having an inwardly-projecting shelf 47 at the lower end formed with a rectangular pocket 48, open at the top and one end and adapted as the seat for a wooden bearing-block 49. This block is conveniently 90 secured from end movement in the pocket by a removable L-shaped keeper 50, which is preferably disposed with the stem upon the under surface of said shelf and the foot portion projecting across the open end of said 95 pocket, and this keeper is suitably fastened in place by adjustable set-bolts, as 51, which pass through suitable apertures in said stem and have screw-threaded engagement with the 100 walls of apertures conveniently formed in the shelf and are of suitable length to project into the pocket thereof and serve as means to raise the bearing-block when desired to 105 compensate for wear. As now considered, the truck-wheel is adjusted laterally by means of 110 a set-bolt 52, having screw-threaded engagement in a suitable aperture formed transversely the bracket 46 concentric with the bearing for the axle of said wheel, and the 115 end of this bolt normally engages the end of said axle, so that the wheel can be set over by turning the set-bolt. This truck is set with the long end of its base extending toward the adjacent end of the carriage-base and the 120 bracket at the back of the carriage, with the bearing-block slidably engaging the surface of the top wall of the track-bed, and the end of the adjacent truss-rod 35 is preferably passed through a suitable aperture in said 125 truck-base and the nut 38 thereon brought to bear upon a seat formed on said base-plate at right angles to said rod, whereby the trucks and carriage-frame are rigidly fastened together, and the truck is still further secured 130 in position by suitable bolts, as 54, which are

passed through apertures in its base-plate and corresponding apertures in the carriage-base.

By arranging the pocket 47 with one end wall open and providing a removable keeper, as 50, the bearing-blocks can be readily replaced when worn by simply removing the keeper, and this may be done without disturbing the position of the trucks when the carriage is in place on the track.

- 10 The feed-works of this machine include a mangle-rack, as 55, which is preferably disposed adjacent the forward end of the track-frame in a vertical position and is operatively connected to carriage 15 by a suitable stem 15 56, Fig. 7, secured at one end to the rack and having a suitable bearing-box, as 57, at the opposite end, which is engaged with a stud 57', fixed to a bracket 58', secured to the base of said carriage on the back side surface.
- 20 This mangle-rack is rendered of suitable length to move carriage 15 reciprocatively the distance required in sawing shingles, and as now considered it comprises an open frame 60, having suitable gear-teeth arranged internally to conveniently form a continuous rack composed of a plurality of sections or runs of teeth, as 58 and 59, which are laterally offset relatively to each other and preferably arranged in different planes. As now considered, the track-section 58 extends along one side of frame 60 and about the ends thereof, while the section 59 extends along the opposite side of said frame, and an endless guide-groove is suitably formed on the frame by 30 providing an outer guide 61 and an inner guide 62, the former consisting of a continuous rib disposed at the outer said edge of the rack-section 58 and the latter consisting of a rim of less diameter than the outer guide conveniently secured in position parallel thereto by suitable bars, as 63, secured to the outer edge of said guides.
- 35 The driver for the mangle-rack includes an operatively-mounted spur-gear for each run 45 or section of teeth, Fig. 4, as a wheel 64, adapted to mesh with the rack-section 59, and a pinion 65, of less pitch diameter than the wheel and adapted to mesh with rack-section 58. As now considered both of these spur-gears are fixedly mounted on one end portion 50 of a horizontally-disposed drive-shaft 66, journaled in suitable bearings; as 67, one of which is mounted on track-bed 20 and the others suitably mounted in the husk-frame to rotatably support the shaft. On the outer extremity of this shaft a suitable guide-roller, as 67', Fig. 4, is conveniently rotatably mounted, so as to engage in the guide-groove with the guide 61 or 62, according to which of the gears 55 are in mesh. This roller is formed with a suitable flange on the outer edge of the periphery, so that said guides will be embraced by said flange and the adjacent side face of the spur-pinion, and a suitable friction clutch-pulley, as 67", is mounted on drive-shaft 66,

and the clutch mechanism of this pulley is operatively connected to a suitably-fulcrumed treadle, as 68, disposed at the position taken by the sawyer, through the medium of a rotatably-mounted rod 69, extending along the front edge of the base of the track-frame, a suitable shifter connected to said rod and the clutch mechanism, and said rod is connected to the treadle by means of a laterally-projecting arm 70, fixed to the rod and a link 71, pivoted to said arm and to one end of said treadle.

In forming the mangle-rack 55 as now considered the different sets of teeth are arranged in different planes, so that the pitch-lines will be separated in conformity with the difference in the pitch radii of the drivers, as 64 and 65, which will thereby pass in and out of mesh with the teeth of respective sections without jarring, and the teeth at the ends of the sections 58 are somewhat reduced in thickness at the points, so as to properly clear the teeth in pinion 65 as the rack passes into and out of mesh with wheel 64.

In the present embodiment the husk-frame 16 includes a suitable base composed of separated side timbers 72, disposed laterally at one side of the track-frame opposite the mangle-rack and joined at the inner ends to the base of the track-frame and connected at the opposite ends by a cross-timber 73. Upon this base suitable stands, as 74, are disposed to support the journals, as 75, of a saw-arbor 76, adapted to carry a suitable shingle-saw 77, and suitable stands 78 of less height than the former stands are secured to said base to carry the journals of a saw-arbor 79, disposed at right angles to arbor 76 and adapted to carry a suitable jointing-saw 80 at the side of the husk-frame nearest the position taken by the sawyer. At this side of said frame a suitable table, as 81, is conveniently mounted to receive the shingles as cut from the block by saw 77, and a suitable movably-mounted jointing-table, as 82, is also conveniently mounted on the husk-frame at this point, to which the shingles are transferred for the purpose of presenting them to the jointing-saw.

The shingle-blocks are securely held in the carriage 15 by means of feed-rollers, as 83 and 83', the former of which is journaled in suitable bearings, as 84, secured to the base-plate 30 of the frame, while the latter is mounted in similar bearings, as 84', secured to a plate, as 85, which is suitably slidably mounted for vertical movement on a cross-bar 86, fixed to the free ends of a suitable carrier consisting of laterally-disposed arms 87, which are pivoted at their free ends to respective end pieces 27 of the carriage-frame adjacent the top by suitable bolts, as 88. The plate 85 is normally yieldingly held in depressed position by coiled springs, as 85', placed at each end of the plate and confined beneath laterally-projecting stops fixed to the carrier, and this

plate is formed with downwardly-extending fingers, as 89, along the lower edge, which curve over the feed-roller 83' and are adapted to assist in securing the shingle-block, and 5 the base-plate 30 is formed with upwardly-extending fingers 90, which curve over the feed-roller 83. To one end of each of these rollers is fixed a suitable ratchet-wheel, as 91, having the teeth unequally spaced, as in the ordinary ratchet-wheels for this purpose. These 10 rollers are operated simultaneously in opposite directions by means of suitable gravity-pawls 92, which are pivotally connected to a vertically-disposed lever 93, which is fulcrumed on a suitable pivot 94, fixedly mounted on the rear end piece 27. These pawls are 15 connected to the lever at opposite sides of its fulcrum, and the free ends thereof rest upon respective ratchet-wheels 91, which are oppositely disposed, so that the lever when operated in one direction serves to turn the feed-rollers in opposite directions, and when operated in the opposite direction both of the 20 pawls ride on the ratchets. These pawls each 25 comprise a stem of suitable size having an enlarged head at the free end, which is formed with an inclined end surface, as 92', having a suitable channel extending with the incline and adapted to slidably receive a substantially 30 rectangular plate 92'', which comprises the bill of the pawl and is formed with an elongated slot adapted to receive a clamping-bolt, as 91', which has screw-threaded engagement in a suitable aperture in the head, whereby 35 the bolt can be loosened to release the bill for adjustment.

The inclined surfaces on the pawls are oppositely disposed relatively to each other, so that the bills will be properly presented to 40 respective ratchet-wheels to rotate the feed-rollers in opposite directions, and the teeth on the ratchet-wheels are properly spaced to cause the pawls to act therewith to move respective feed-rollers a short and a long turn 45 alternately, so that the shingle-block will be properly set.

The lever 93 is operative by means of a cam, as 95, Fig. 10, properly disposed to lie in the path of movement of the upper end of the lever as the carriage travels, and a cam-roller 96 is conveniently journaled on the upper end of said lever so as to engage in the track in said cam. As now considered, this cam comprises a substantially S-shaped plate 97, formed with 55 a downwardly-extending rib 98 on the bottom surface, which is bent substantially midway its length to approximately a right angle, and a second rib 99 set parallel to one stem of the first rib and at suitable separation therefrom 60 to leave a track between said ribs for the passage of the roller 96. This cam-plate is adjustably secured on the lower surface of a horizontally-disposed bracket 100, consisting of a section of plate metal having a downwardly-projecting rib 99', which acts as a for-

wardly-extending continuation of rib 99, and this bracket-plate is suitably mounted on the beam of the track-frame, so as to project from the rear upper edge, with said rib 99' parallel to the line of travel of the carriage, by means of suitable lugs 101, secured to said plate and beam by bolts or the like, and the cam-plate is adjustably mounted on the bracket, with the parallel ribs at the position in which the lever lies when the carriage is resting in retracted position, by means of a pivot-bolt 102, disposed in a suitable aperture formed in the cam-plate adjacent the forward end thereof and back of rib 98 and in a corresponding aperture in the bracket. This cam-plate is conveniently secured in adjusted position by means of a clamping-bolt 103, disposed in a suitable aperture in the bracket and passing through a segmental slot 104, formed in said plate concentric with the pivot-bolt 102, 85 whereby the cam-plate can be readily adjusted to vary the throw of the lever 93 by loosening the clamping-bolt and swinging the plate about the pivot-bolt.

The free end of the frame which carries the upper feed-roller 83' is raised and lowered through the medium of a horizontally-disposed lever 105, operably mounted on a suitable fulcrum-bolt 106, secured in a standard 107, fixed to the top plate 29 of the carriage, 95 and this lever is operatively connected to said frame by a vertically-disposed rod 108, pivotally connected thereto and to the plate 85, and is conveniently operated by a foot-lever, as 109, pivotally mounted at the front of the machine and connected to said upper lever by a vertically-disposed rod 110, having a suitable link connection with the foot-lever, as a chain and ring 110', which permits the rod to swing freely as it travels with the carriage. 105

To the free end of the foot-lever 109 is secured one end of a suitable line 111, which extends upwardly and over a sheave in a block 112, fastened to the beam of the track-frame, and then downwardly to the base of the machine, and the clutch-shifting rod 69 is provided with a laterally-projecting stem having a loop 115 at the free end, through which the pendent end portion of this line passes freely, and at the end of the line a suitable bumper is secured, as a weight 116, which contacts said loop as the line is drawn by depressing said foot-lever to raise the upper feed-roll, and thereby simultaneously operates the shifting-rod, which frees the clutch in pulley 67 and renders the feed-works inactive.

In the present embodiment the mangle-rack is yieldingly supported by means of a spring 117, Fig. 12, which is seated on the carriage 125 and engaged with the stem 56, and as now considered the spring comprises a flat bar of resilient metal suitably fastened to the carriage by one end and rendered of suitable length to project forwardly and engage said 130

stem at a point substantially midway its length, so as to bear upwardly on the stem, and thereby yieldingly support the mangle-rack, and thus insure a smoother travel of the 5 rack about the driver.

The operation of this machine will be readily understood from the foregoing description by those familiar with this class of shingle machinery; but, briefly stated, it is substantially as follows: Granted the application of power to drive the pulleys of the machine the sawyer takes a position at point A, Fig. 1, presses down on foot-lever 109 and places a shingle-block between the feed-rollers and 10 then allows the lever to retract, so that the carrier having the upper feed-roller will close by gravity upon the block. The feed-works are then started by throwing in the clutch in pulley 67, and the carriage advances toward 15 saw 77, and the roller on lever 93 enters track in cam 95, and the lever is thereby actuated during primary advancing action of the carriage and serves to retract the pawls 92 relatively to the teeth on respective ratchet-wheels. As the carriage is returning the 20 cam-roller passes through the cam-track during the latter portion of the reverse action, and the lever 93 is thereby reversed and serves to advance the pawls, and thereby operate the 25 feed-rollers, to set the block in the ordinary and well-known manner. After the machine is once started, as above set forth, the operation continues uninterrupted until the block is reduced to shingles, and during this period 30 the sawyer is at liberty to transfer shingles from the receiving-table 81 to the movable table 82 for the purpose of presenting them to the jointing-saw 80.

By employing the mangle-rack in the feed-works, as heretofore described, the carriage is given a positive motion with a return speed considerably greater than the feed, and the speed is gradually reduced and increased at each end of the travel as the segmental portions of the rack travel about the driver, and the carriage is thereby reversed without any perceptible jerk or jar. Furthermore, by forming the carriage with the truss-rods, as heretofore set forth, the structure is rendered 45 rigid, and the end pieces are firmly braced against lateral strains.

Having thus described my invention, what I claim as new, and desire to secure by Letters Patent of the United States of America, is—
55 1. In a shingle-machine, an upright carriage comprising an elongated base, a frame composed of vertical end pieces, plates connecting the ends of the end pieces, a lug on the upper end of each end piece, diagonally-disposed truss-rods extending from the base of the frame to the lugs, and opposed work-feeding means carried by the end pieces at the top and bottom thereof respectively, substantially as described.

2. In a shingle-machine, an upright carriage comprising an elongated base, a frame supported centrally on said base and composed of oppositely-disposed end pieces formed of plate metal, each comprising a stem having a foot portion extending from one side edge, 65 a downwardly-extending heel on the free end of the said portion, a bracket extending from the upper end of the stem in the same direction as the said foot and having a laterally-projecting lug on the outer surface and an upwardly-projecting lug at the outer end, a top plate secured to the upper ends of said 70 upwardly-projecting lugs, a bottom plate, a diagonally-disposed truss-rod at each side of said frame engaged with said laterally-projecting lugs and extending to and secured to said base adjacent the ends, and opposed work-feeding rollers carried by the end pieces at the top and bottom thereof respectively, substantially as described. 75

3. In a shingle-machine, an upright carriage comprising an elongated base, a channel-beam supporting a track, trucks supporting the base and having wheels running on said track, brackets extending from the trucks, 80 shoes carried by the brackets and bearing against the under surface of the top of the channel-beam, means for adjusting said shoes, means carried by the truck for adjusting the wheels laterally, a frame carried by the base 85 comprising end pieces, opposed work-feeding means supported by the end pieces at the top and bottom thereof respectively, and means for moving the carriage, substantially as described. 90

4. In a shingle-machine, a track-frame, a channel-beam supported upon the bottom of the frame, tracks upon the channel-beam and the top of the frame, a carriage having an elongated base provided with trucks engaging 100 the channel-beam track, a frame comprising vertical end pieces supported on said base, plates secured to the top and bottom ends of the end pieces, guides on the top plate slidably engaging the track on the top of the track-frame, a diagonally-disposed truss-rod connecting the base with the upper portion of each end piece, opposed work-feeding means carried by the end pieces at the top and bottom thereof, respectively, and means for reciprocating the carriage, substantially as described. 105

5. In a shingle-machine, a track-frame, an upright carriage comprising an elongated base, a channel-beam supported upon the bottom of the track-frame, a track upon the top of the channel-beam, trucks supporting the base of the carriage each comprising a base-plate formed with journal-boxes on the bottom surface, and a wheel-opening between 110 said boxes, a truck-wheel running upon the track and adapted to be moved laterally between the boxes, a downwardly-extending 115

- bracket from the base-plate having an inwardly-projecting pocket, a bearing-block in said pockets engaging the under surface of the channel-beam, a removable keeper under 5 said block, means to adjust said wheel laterally, means for raising said bearing-block, and opposed work-feeding means carried at the top and bottom of said carriage, substantially as described.
- 10 6. In a shingle-machine, a track-frame, an upright carriage comprising an elongated base, a channel-beam supported upon the bottom of the truck-frame, a track upon the top of the channel-beam, trucks supporting the 15 base of the carriage each comprising a base-plate formed with axle-bearings, a downwardly-projecting bracket from one side of the base-plate having an inwardly-projecting shelf formed with a pocket, a bearing-block 20 removably seated in the pocket and contacting with the under surface of the top of the channel-beam, a substantially L-shaped keeper disposed on the shelf with its foot across one end of the pocket, set-bolts threaded in the 25 bottom of the shelf and passing through the stem of the keeper, and opposed work-feeding means carried by the carriage at the top

and bottom thereof respectively, substantially as described.

7. In a shingle-machine, an upright carriage 30 comprising an elongated base, trucks supporting the base, a channel-beam having a track engaged by the trucks, a frame disposed upon the base composed of end pieces connected by top and bottom plates, a track supported adjacent the upper ends of the end pieces, slides secured to the top plate engaging the said track, truss-rods connecting the upper portions of the end pieces and the ends of the base, opposed work-feeding rollers carried by 40 the end pieces at the top and bottom thereof respectively, a plate having flexible fingers secured adjacent each roller, gravity-pawl 45 carried by the end pieces for feeding the rollers, means for moving the top roller, and means for reciprocating the carriage, substantially as described.

Signed at Fairhaven, Washington, this 28th day of January, 1903.
